UNITED STATES PATENT OFFICE.

FORREST WILLIAM MANKER, OF JACKSON HEIGHTS, NEW YORK, ASSIGNOR TO SURFACE COMBUSTION COMPANY, OF NEW YORK, N. Y., A CORPORATION OF NEW YORK.

WIRE-HEATING OVEN.

Application filed September 12, 1925. Serial No. 55,929.

This invention relates to improvements in furnaces and more particularly to an improved oven in which coils or bundles of wire may be heated for drying after they 5 have been pickled to remove scale.

It is an object of the invention to provide an oven for the purpose specified which shall be simple in construction, efficient in operation, and which may be heated with fluid fuel.

Another object is to provide a furnace construction in which the oven may be heated in such a manner that the hot air in the oven may circulate freely around the 15 work to be dried or heated, the circulation of air being set up by convection currents within the oven.

A still further object is to provide an oven which may be heated by means of a 20 longitudinally extending tunnel arranged at the bottom of the oven, means being provided for leading the products of combustion through a radiator arranged within the oven in order to more effectually utilize the 25 heating value of the fuel and to assist in setting up convection currents within the oven.

The above and other objects will appear from the detailed description taken in connection with the accompanying drawings 30 forming part of this specification.

Referring to the drawings:

Figure 1 is a vertical longitudinal section through the improved furnace or wire-heating oven, showing the preferred arrangement of parts and how the radiator is disposed within the oven;

Figure 2 is a vertical transverse section taken on line 2—2 of Fig. 1 and showing the base of the furnace provided with spaced piers or runways on which wire-laden, and wheeled vehicles (not shown) are adapted to be supported, and

Fig. 3 is a vertical transverse section taken on line 3—3 of Fig. 1, showing constructional features of the furnace.

In the drawings, the side walls of the furnace or oven are indicated at 10, the roof or arch of the same at 12, and the doors at the ends of the oven at 14. The side walls of the furnace are supported on a suitable base 18. Extending longitudinally of the base is a flue or tunnel, generally indicated at 20, this flue being built of suitable refractory material and having an opening 22 at one end through which fluid fuel such as oil or

gas may be entered into the tunnel, any suitable type of burner being utilized for introducing the fuel into the tunnel.

The products of combustion formed by the burning fuel pass out of the flue or tunnel through an opening or outlet 24 at the far end thereof. Disposed over the opening 24 is an elbow 26 and connected with the elbow is a radiator 28, preferably in the form of a pipe or conduit, bent back 60 upon itself, the lower run of the pipe being disposed somewhat above the top of the tunnel. The gases passing through the radiator pass from the same through a suitable riser 30, which is in connection with a suitable flue 32 leading to a stack. A damper 34 is preferably provided in the riser 30 to permit control of the rate of passage of the products of combustion through the radiator. 65

That end of the radiator farthest away from the tunnel outlet 24 is preferably provided with a conduit 36 which leads from the tunnel adjacent the firing end thereof to permit by-passing of some of the hot gases 70 to the adjacent portion of the radiator. This conduit is preferably provided with a damper 38 for controlling the flow of the hot gases into the radiator. 75

The radiator is suspended in a vertical 80 plane within the oven in any suitable manner, as by means of strap-hangers 40 suspended from cross-rods 42. The radiator and tunnel are located midway between the walls 10 of the oven which is thus divided 85 into two equal parts, one part on each side of the radiator and the tunnel.

Rising from the base of the furnace at each side of the tunnel is a plurality of piers 44. These piers are provided with tracks or ways 46 to permit wheeled vehicles to be moved therealong, it being contemplated that the wire or work to be heated will be placed on the wheeled vehicles, such as trucks. The tracks are conveniently connected by transverse ties 48, as indicated in Fig. 2. The piers are spaced from each other to form channels 49 and from the adjacent side walls of the oven to form channels 49'. 90

Referring to Figs. 2 and 3, it will be noted that the side walls of the tunnel 20 are not of the same thickness throughout their length, the walls being thicker in the first part of the tunnel so as better to withstand 100

- the high temperature of the burning gases, the thickened portion of the walls being indicated at 50. The tunnel 20 is preferably capped with an arch 52, which is of equal length with the thickened side walls. That portion of the tunnel having the thickened side walls 50 and the arch 52 may properly be termed the combustion chamber of the tunnel. The other portion of the tunnel 10 may conveniently be termed the expansion chamber of the tunnel. The side walls of the expansion chamber are indicated at 54 and the cover tile at 56. These parts are 15 preferably of less thickness than the corresponding parts of the combustion-chamber-part of the tunnel. It will also be noted that the expansion chamber is of larger cross-section area than the combustion chamber.
- 20 The piers 44 nearest the tunnel are contiguous the combustion-chamber-part thereof, but are in spaced relation to the other part whereby channels 57 are formed. The piers are provided with lateral passages 58 25 to permit free circulation of the heated air between the various channels.

By reference to Fig. 1 it will be noted that the tracks 46 are preferably arranged on a gradient so as to facilitate the movement of the trucks or wheeled vehicles through the oven.

What is claimed is:

1. A furnace comprising an oven, a tunnel in which fuel may be burned for heating the oven extending longitudinally of the oven midway its sides and beneath the floor thereof, means for leading the products of combustion formed in said tunnel through the oven for further heating the latter comprising a radiator extending from the top of the flue to the top of the oven, and open top channels extending parallel to the flue in the floor of the oven on both sides of the tunnel and connected by lateral passages 40 whereby air may circulate freely along the sides of the tunnel to be heated thereby and 45 may circulate below work supported on the floor across said channels.
2. A furnace comprising an oven, a tunnel in which fuel may be burned for heating the oven extending longitudinally of the same midway its sides, means for supporting the work to be heated comprising elevated tracks the tops of which are substantially on a level with the top of the tunnel, said tracks being in spaced relation with respect to each other and the sides of the oven and the sides of the tunnel whereby air may 50 freely circulate below the work supported on the tracks and may come in contact with the sides of the tunnel to be heated thereby, and means for leading the products of combustion formed in said tunnel through the oven for further heating the latter, said means comprising a conduit leading from one end of the tunnel back toward the other end thereof and thence upwardly and forwardly and finally out through the roof of the oven, said conduit dividing the oven into two equal 55 parts.
3. A furnace comprising an oven, a tunnel in which fuel may be burned for heating the oven extending longitudinally of the same midway its sides, means for supporting the work to be heated comprising elevated tracks the tops of which are substantially on a level with the top of the tunnel, said tracks being in spaced relation with respect to each other and the sides of the oven and the sides of the tunnel whereby air may 60 freely circulate below the work supported on the tracks and may come in contact with the sides of the tunnel to be heated thereby, and means for leading the products of combustion formed in said tunnel through the oven for further heating the latter, said means comprising a conduit leading from one end of the tunnel back toward the other end thereof and thence upwardly and forwardly and finally out through the roof of the oven, said conduit dividing the oven into two equal 65 parts.
4. A furnace comprising an oven, a tunnel in which fuel may be burned for heating the oven extending longitudinally of the same midway its sides, means for supporting the work to be heated comprising elevated tracks the tops of which are substantially on a level with the top of the tunnel, said tracks being in spaced relation with respect to each other and the sides of the oven and the sides of the tunnel whereby air may 70 freely circulate below the work supported on the tracks and may come in contact with the sides of the tunnel to be heated thereby, and means for leading the products of combustion formed in said tunnel through the oven for further heating the latter, said means comprising a conduit leading from one end of the tunnel back toward the other end thereof and thence upwardly and forwardly and finally out through the roof of the oven, said conduit dividing the oven into two equal 75 parts.
5. A furnace comprising an oven, a tunnel in which fuel may be burned for heating the oven extending longitudinally of the same midway its sides, means for supporting the work to be heated comprising elevated tracks the tops of which are substantially on a level with the top of the tunnel, said tracks being in spaced relation with respect to each other and the sides of the oven and the sides of the tunnel whereby air may 80 freely circulate below the work supported on the tracks and may come in contact with the sides of the tunnel to be heated thereby, and means for leading the products of combustion formed in said tunnel through the oven for further heating the latter, said means comprising a conduit leading from one end of the tunnel back toward the other end thereof and thence upwardly and forwardly and finally out through the roof of the oven, said conduit dividing the oven into two equal 85 parts.
6. A furnace comprising an oven, a tunnel in which fuel may be burned for heating the oven extending longitudinally of the same midway its sides, means for supporting the work to be heated comprising elevated tracks the tops of which are substantially on a level with the top of the tunnel, said tracks being in spaced relation with respect to each other and the sides of the oven and the sides of the tunnel whereby air may 90 freely circulate below the work supported on the tracks and may come in contact with the sides of the tunnel to be heated thereby, and means for leading the products of combustion formed in said tunnel through the oven for further heating the latter, said means comprising a conduit leading from one end of the tunnel back toward the other end thereof and thence upwardly and forwardly and finally out through the roof of the oven, said conduit dividing the oven into two equal 95 parts.
7. A furnace comprising an oven, a tunnel in which fuel may be burned for heating the oven extending longitudinally of the same midway its sides, means for supporting the work to be heated comprising elevated tracks the tops of which are substantially on a level with the top of the tunnel, said tracks being in spaced relation with respect to each other and the sides of the oven and the sides of the tunnel whereby air may 100 freely circulate below the work supported on the tracks and may come in contact with the sides of the tunnel to be heated thereby, and means for leading the products of combustion formed in said tunnel through the oven for further heating the latter, said means comprising a conduit leading from one end of the tunnel back toward the other end thereof and thence upwardly and forwardly and finally out through the roof of the oven, and a damper-controlled conduit leading directly from the return bend in the conduit to the adjacent end of the tunnel. 105
8. A furnace comprising an oven, a tunnel in which fuel may be burned for heating the oven extending longitudinally of the same midway its sides, runways extending parallel to the tunnel and separated from each other and the adjacent walls of the oven and tunnel by channels which permit the air in the oven to circulate freely below work supported on the runways, and means for conducting the products of combustion formed in the tunnel through the oven along an upright plane midway the sides of the oven. 110
9. A furnace comprising an oven, a tunnel in which fuel may be burned for heating the oven extending longitudinally of the same midway its sides, runways extending parallel to the tunnel and separated from each other and the adjacent walls of the oven and tunnel by channels which permit the air in the oven to circulate freely below work supported on the runways, and means for conducting the products of combustion formed in the tunnel through the oven along an upright plane midway the sides of the oven. 115
10. A furnace comprising an oven, a tunnel in which fuel may be burned for heating the oven extending longitudinally of the same midway its sides, runways extending parallel to the tunnel and separated from each other and the adjacent walls of the oven and tunnel by channels which permit the air in the oven to circulate freely below work supported on the runways, and means for conducting the products of combustion formed in the tunnel through the oven along an upright plane midway the sides of the oven. 120
11. A furnace comprising an oven, a tunnel in which fuel may be burned for heating the oven extending longitudinally of the same midway its sides, runways extending parallel to the tunnel and separated from each other and the adjacent walls of the oven and tunnel by channels which permit the air in the oven to circulate freely below work supported on the runways, and means for conducting the products of combustion formed in the tunnel through the oven along an upright plane midway the sides of the oven. 125
12. A furnace comprising an oven, a tunnel in which fuel may be burned for heating the oven extending longitudinally of the same midway its sides, runways extending parallel to the tunnel and separated from each other and the adjacent walls of the oven and tunnel by channels which permit the air in the oven to circulate freely below work supported on the runways, and means for conducting the products of combustion formed in the tunnel through the oven along an upright plane midway the sides of the oven. 130

- greater cross-sectional area from a point intermediate its ends towards its discharge end, a radiator having connection with the discharge end of the tunnel whereby the products of combustion formed in the tunnel may pass through the radiator to heat the oven, said radiator comprising a pipe bent back upon itself, the coils of the radiator being arranged in a vertical plane. 5
- 10 7. A furnace comprising an oven, a tunnel extending longitudinally of the oven along the bottom thereof and adapted to be fired from one end, said tunnel being of greater cross-sectional area from a point intermediate its ends towards its discharge end, a radiator having connection with the discharge end of the tunnel whereby the products of combustion formed in the tunnel may pass through the radiator to heat the oven, said radiator comprising a pipe bent back upon itself, the coils of the radiator being arranged in a vertical plane, and longitudinally extending piers on both sides of the tunnel adapted to support the work to 15 be heated. 20 25
8. A furnace comprising an oven, a tunnel within the oven in which fuel may be burned for supplying heat to the oven, a radiator within the oven through which the products of combustion formed in the tunnel may pass on their way out of the oven, said radiator being so disposed within the oven that passageways for the introduction of the work to be heated are formed between the radiator and the side walls of the oven, and means extending along both sides of the tunnel for supporting the load of the said work, said means being of openwork construction to permit free circulation of air along the sides of the tunnel. 30 35 40
9. A furnace comprising an oven, a tunnel within the oven in which fuel may be burned for supplying heat to the oven, means within the oven forming a closed path by which the products of combustion formed in the tunnel may pass out of the oven, and means extending alongside the tunnel for supporting the load of the work to be heated, the side walls and top of the tunnel being exposed to the circulation of air within the oven. 45 50

In testimony whereof I affix my signature.

FORREST WILLIAM MANKER.
